UNITED STATES PATENT OFFICE

ALBERT KINDELMANN, OF FLORAL PARK, AND EWALD BOECKING, OF BROOKLYN, NEW YORK, ASSIGNORS TO INTERNATIONAL PROJECTOR CORPORATION, OF NEW YORK, N. Y., A CORPORATION OF DELAWARE

FILM GATE LOCK

Application filed November 29, 1929. Serial No. 410,439.

This invention relates to motion picture machines, and more particularly to a new and improved film gate lock.

An object of the invention is to provide a lock for preventing movement of the film gate when the door of the projection head is closed.

Another object is to prevent the door of the projection head from being closed when the film gate is in open position.

A further object of the invention is to provide a positive securing means for the film gate to prevent movement thereof during the operation of the motion picture machine.

The invention is particularly applicable to a motion picture projection machine having a film gate which moves laterally to permit the insertion of a film, and a door for closing the projection head during the operation of the machine.

The above objects and others which will be apparent as the nature of the invention is disclosed are accomplished by providing a latch member on the inside of the door in position to contact with the edge of the film gate when the film gate is open and to prevent closure of the door. The latch also contacts with the rear surface of the film gate when the door is closed and thereby positively secures the film gate in operative position.

The invention also consists in certain new and original features of construction and combinations of parts hereinafter set forth and claimed.

Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

Fig. 1 is an elevation of the projection head of a motion picture machine constructed in accordance with the present invention;

Fig. 2 is a horizontal section through the film gate and latch member;

Fig. 3 is an enlarged detailed view of the latch member; and

Fig. 4 is a horizontal section through the film gate and latch member showing the film gate in open position.

Like reference characters denote like parts in the several figures of the drawings.

In the following description and in the claims parts will be identified by specific names for convenience, but they are intended to be as generic in their application to similar parts as the art will permit.

Referring to the drawings more in detail the invention is shown in Fig. 1 as applied to the projection head 10 of a motion picture projection machine. Said projection head has an upper film magazine 11 and lower film magazine 12 associated therewith in a manner well known in the art. The projection head includes upper feed sprocket 13, upper film gate 14, intermittent sprocket 15, idler sprocket 16, lower film gate 17, continuous drive sprocket 18 and feed sprocket 19, over which the film is threaded in the order named. The projection head 10 is closed by a door 20 which is hinged thereto as by hinge 21 and secured by suitable latch mechanism 22. The particular form of apparatus, however, forms no part of the invention and will not be set forth in detail.

Film gate 14 comprises a casting 25 (Figs. 2 and 4) to which pressure shoes 26 are secured in any well known manner and held in engagement with the film by spring 27. Film gate 14 registers with an aperture plate including a housing 30 having film guides 31 secured thereto. Light shield 32 may be secured to said housing in alignment with aperture 33. Fire gate 34 is slidably mounted for movement in groove 35 in said housing.

Film gate 14 may be controlled by rod 40 which is slidably mounted in housing 30 and provided with operating handle 41. This particular form of film gate and aperture plate is disclosed by way of illustration only and not as a limitation of the present invention.

The film gate lock comprises a latch member 45 which is preferably formed of slight-

ly resilient material and secured to the inner surface of the door 20 as by screw 46. Latch member 45 is provided with an inturned flange 47 which is in position to contact with the outer face of casting 25 as shown in Fig. 4, when the film gate is in open position thereby preventing the door 20 from being closed. When the film gate is in closed position flange 47 contacts with the rear surface of casting 25 as illustrated in Fig. 2 and firmly secures the film gate in that position. Member 45 is preferably formed sufficiently resilient to hold the film gate against undesired movement while the machine is being operated and to insure the complete closure thereof.

The above described mechanism eliminates any tendency to vibrate which the film gate might otherwise have and forms a positive lock for holding the film gate in closed position while the projection machine is being operated. Furthermore, the latch operates as a safety device for preventing the operator from closing the door and starting the operation of the machine without first closing the film gate.

While certain novel features of the invention have been shown and described and are pointed out in the annexed claims, it will be understood that various omissions, substitutions and changes in the forms and details of the device illustrated and in its operation may be made by those skilled in the art without departing from the spirit of the invention.

What is claimed is:

1. In a motion picture machine having a film gate and a closure member, means carried by said closure member and engaging said gate for locking said film gate in closed position when said member is closed and for preventing said member from being closed when said film gate is in open position.

2. In a projection head of a motion picture projection machine, a film gate, a closure member for completely closing said projection head, and means carried by said member and engaging said gate for locking said film gate in closed position when said member is closed.

3. In combination with a projection head, a film gate, a door for closing said projection head, and locking means carried by said door and engaging said gate for locking said film gate in closed position when said door is closed.

4. In combination with a projection head, a film gate, a door for closing said projection head, and a resilient latch carried by said door in a position to contact with the rear surface of said film gate when said film gate is closed for resiliently securing said film gate in closed position.

5. In a projection head, a film gate including a casting, a closure for said projection head comprising a door and a latch member

carried by said door and having an inturned flange adapted to contact with the edge of said casting when said film gate is open for preventing closure of said door and to contact with the rear of said casting when said film gate is closed for locking said film gate in closed position during normal operation of the machine.

6. In a projection head, a film gate including a casting, a closure for said projection head comprising a door and a latch member of resilient material carried by said door and having an inturned flange positioned to contact with the edge of said film gate when said film gate is open and thereby prevent closure of said door, said flange being adapted to resiliently secure said film gate in closed position when said door is closed.

ALBERT KINDELMANN.
EWALD BOECKING.
